(57) **CLAIM**

The ornamental design for a handle, as shown and described.

DESCRIPTION

FIG. 1 is a perspective view of the handle showing my new design;

FIG. 2 is a front side view of the handle;

FIG. 3 is a back side view of the handle;

FIG. 4 is a left side view of the handle;

FIG. 5 is a right view of the handle;

FIG. 6 is a top view of the handle; and,

FIG. 7 is a bottom view of the handle.

The broken lines in the drawings depict portions form no part of the claimed design.
